DESIGN FOR A POP TOY

Frank Passio, Philadelphia, Pa.

Application November 19, 1946, Serial No. 134,906

Term of patent 3½ years

(Cl. D34—15)

To all whom it may concern:

Be it known that I, Frank Passio, a citizen of the United States, residing in the city of Philadelphia, in the county of Philadelphia and State of Pennsylvania, have invented a new, original, and ornamental Design for a Pop Toy, of which the following is a specification, reference being had to the accompanying drawing, forming part thereof.

In the drawing,

Fig. 1 is a perspective view of a Pop Toy, showing my new design, the view taken from the front;

Fig. 2 is a similar view, taken from the side; and

Fig. 3 is a perspective view of the plug member forming part of the design.

I claim:

The ornamental design for a Pop Toy, substantially as shown.

FRANK PASSIO.
